UNITED STATES PATENT OFFICE.

WILLIAM C. STEWART, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

HEEL-SEAT-FITTING MACHINE.

Application filed October 25, 1924. Serial No. 745,892.

This invention relates to the manufacture of shoes and is illustrated herein as embodied in a heel-seat fitting machine adapted to trim the heel-seats of soles of shoes for the reception of heels.

In the manufacture of shoes to which wood and some other types of heels are to be attached, the heel-seat portions of the soles of the shoes are prepared for the attachment of the heels by what is known as the heel-seat fitting operation. Heels of the types referred to are formed with concave attaching surfaces, and it is the purpose of the heel-seat fitting operation to trim the heel-seat portion of the sole so that the periphery of the concave attaching surface of the heel will contact closely with the adjacent shoe upper, the margin of the heel-seat portion of the sole being thus completely covered by the attached heel and concealed from view in the completed shoe. Moreover, the shape to which the heel-seat of the sole of a shoe is trimmed by the heel-seat fitting operation should be complementary to the shape of the attaching surface of the heel to be attached so as to provide a good bearing for the heel upon the sole.

The stock trimmed from the heel-seat portion of the sole of a shoe during the heel-seat fitting operation is roughly of a horseshoe-shaped form, a breast cut or cuts being made transversely of the sole to receive the breast of the heel. In order that a shoe may have a neat and trim appearance and that its heel may be securely attached, it is necessary that the trimming of the heel-seat portion of its sole to fit the heel which is to be attached be done accurately. Thus the position of the breast cut longitudinally of the sole of a shoe and both the width and length to which the heel-seat is trimmed must be varied in accordance with the size and style of the heel to be attached.

When the heel-seat fitting operation is performed by hand, it is customary for the operator to locate the breast cut by applying to the sole the particular heel which is to be attached and marking on the sole the position occupied by the breast of the heel. This

mark is used to determine the forward extent 50 of the trimming operation, but the rearward extent of the trimming and the amount of stock trimmed off at the sides of the heel-seat depend upon the judgment and skill of the operator, and there is a distinct tendency when performing the operation by hand to remove too much stock since it is practically impossible to attach the heel if too little stock is removed, and it is very difficult to trim off by hand exactly the right amount. 60

Heel-seat fitting machines have been proposed in which the position of the breast cut and the forward extent of the trimming cut were determined by the use of the heel which was to be attached to a shoe, or by a heel 65 like that one, as a templet, the machine being provided with relatively movable gage members arranged to contact with the breast and the rear of the heel and operating to control the performance of the operation. It is 70 an object of the present invention to provide a heel-seat fitting machine having improved means for controlling the trimming of the heel-seat portion of the sole of a shoe. To this end the machine herein disclosed is provided with means for measuring both the 75 length and the width of the heel which is to be attached to the shoe or a heel like that which is to be attached to the shoe operated on, thereby controlling the position of the 80 breast cut, the length of the trimming cut and the width to which the heel-seat portion is trimmed. The illustrated machine, moreover, is arranged so that when certain of its parts are moved into inoperative position at 85 the conclusion of the operation on each shoe, parts of the measuring device are withdrawn from the heel which has controlled the trimming operation so that, if necessary, the heel may be readily removed and replaced by 90 another. When the machine is again started to operate on the next shoe, the parts of the measuring device which have been withdrawn move back into engagement with the heel so as to control the heel-seat fitting 95 operation in accordance with the dimensions of that heel.

With the above and other objects and fea-

tures in view the invention will now be described in connection with the accompanying drawings, and pointed out in the claims.

In the drawings,

5 Fig. 1 is a perspective view of a heel-seat fitting machine embodying my invention;

Figs. 2 and 3 are side and plan views respectively of the heel-measuring devices and the interconnected templet-controlling mechanism of the machine of Fig. 1; and

10 Fig. 4 is a sectional view illustrating the trimming operation.

The present invention is disclosed as embodied in a machine of the type disclosed in 15 Letters Patent of the United States No. 1,661,391, granted March 6, 1928, on my co-pending application and having Serial No. 738,449, filed September 18, 1924 to which reference should be had for a complete disclosure of parts not fully described 20 herein. In the illustrated machine a recessed bed plate 10 is supported upon legs 12 and 14 which are held rigid by spacing bars 16 and upon which there is mounted a cross frame 18 carrying a work-supporting post 20 provided with a last spindle. Curved jaws or crease plates 22 are mounted for movement in the bed plate 10 under the control of a hand lever 24 and 25 are adapted to receive and close in upon the rand crease of a shoe supported upon the spindle of post 20.

Mounted for sliding movement upon the upper part of the bed plate 10 is a sliding table 26 comprising two parallel plates which may be moved toward and away from the operator under the control of a manually operated lever 28. Actuation of the lever 28 operates to bring the sliding table 30 forward, working through a rod 34 to raise the post 20 in order to hold the work firmly in engagement with the crease plates 22. The sliding table supports a rotary milling cutter 35, which is mounted on the 45 rotor shaft or an extension of the rotor shaft of an electric motor 30, as shown at 46 (see Figs. 1 and 3). Shaft 46 passes through a sleeve 29 formed rigid with a disk 32 (Fig. 1) slidable between the two plates of the 50 table 26. The electrical supply for the motor 30 is doubly controlled by a manual switch 31 and an automatic switch 33 which is so arranged to contact with the sliding table 26 that it will disconnect the motor 55 from its source of supply whenever the table is moved to its rear or inoperative position.

The path of movement of the rotary cutter is controlled by an adjustable templet comprising plates 36 and 38 (Fig. 3) pivoted at 40 and 42 to the sliding table 26 and provided with a horseshoe-shaped slot 44 for controlling the path of movement of shaft 46, on which the rotary cutter is mounted. The plates of the adjustable 65 templet are provided with overlapping edges

so that the continuity of the slot 44 is not broken in consequence of their adjustment, and the forward ends of the plates are joined by a spring 48 tending to close the templet to bring the spread of slot 44 to its 70 narrowest condition. An enlarged portion or vestibule 50 of the slot 44 is provided for the reception of the shaft 46 of the rotary cutter during the time that the cutter is not actually in trimming operation.

75

The driving motor 30 is supported upon a manually operated lever 52, which in turn is pivoted upon another manually operated lever 54 extending in an angular direction to the first lever, and by means of these levers the operator is able to cause the rotary cutter to pass completely around the horse-shoe-shaped slot to effect the trimming operation by means of which the rear end of the sole is beveled to form the heel-seat.

85

In order to complete the trimming operation by making a breast cut, the machine has a breast cutting knife 60 carried by a sliding bar 62 which is mounted for movement transversely of the work and of the machine in bearings in a carriage 64 mounted for forward and rearward adjustment in the bed 10 of the machine. Actuation of the breast cutting knife 60 is effected by movement of a treadle 70 connected to the sliding bar 62 by means of a treadle rod 72 and a bell crank lever 74. A spring-controlled member 76 upon the treadle rod 72 is connected with the post 20 so that the post is elevated to hold the work in close engagement with the crease plates when the treadle 70 is depressed to actuate the breast cutting knife 60, as disclosed in said Letters Patent No. 1,661,391.

95

100 A stop 66 (Fig. 1) carried by carriage 64 and extending across the forward portion of the horseshoe-shaped path of movement of sleeve 29 limits the forward extent of the path of the rotary cutter in accordance with the position of the breast cut.

105

In order to enable the operator to control and adjust the action of the machine so as to fit shoes of various sizes to receive correspondingly sized heels, the illustrated machine is provided with a hand-wheel 80 115 screw-connected to the carriage 64 which carries the breast cutting knife 60 and the stop 66 so that by rotating the hand-wheel carriage 64 may be adjusted from the front to the rear of the machine in order properly 120 to position the breast cut and to limit the forward extent of the trimming cut.

115

125 On account of the differences in the styles and shapes of wood heels and the consequent differences in the lengths and widths of the heel-seats of the shoes to which the heels are to be attached, it is found desirable to provide mechanism by means of which the heel-seat portion of a heel may be measured upon the machine and the adjust- 130

ment of the machine may be directly dependent upon the measurements of the heel itself. To this end, the heel used is the one which is to be applied to the particular shoe 6 or one like that heel, and this heel controls both the length and the width to which the heel-seat is trimmed. The illustrated machine has a length-measuring device comprising a fixed member 82 secured to the 10 side of the bed plate 10 for engaging the rear of the heel and a heel breast gage 84 secured to and movable with the adjustable carriage 64. Heel breast gage 84 is provided with a bottom plate 85 for supporting an inverted heel, as indicated in Figs. 2 and 3, so that after the heel has been positioned on bottom plate 85, rotation of the hand-wheel 80 will move the carriage 64 to bring the heel in contact with the gage members 82 and 84, there- 20 by positioning the knife 60 and the stop 66 to make the breast cut and to limit the forward movement of the rotary cutter in accordance with the length of the heel. In order to adjust the pivoted templet plates 25 36 and 38 in accordance with the width of the heel measured, the machine is provided with a lever 86 pivoted at 88 upon the sliding table 26 and provided with depending pins received within suitably shaped slots 30 90 which are so arranged that the rotation of the extended end of the lever 88 toward the front of the machine will be effective to spread apart the templet plates against the tension of the spring 48. The means pro- 35 vided for measuring the width of the heel are interconnected with the adjusting lever 86 so that the lateral control of the adjustable templet is directly dependent upon the width of the heel being measured.

40 The means for measuring the width of the heel and controlling the lateral adjustment of templet plates 36, 38 comprises a plate 94 carried by a link 92 for engagement with the side of a heel supported on the bottom plate 85 of the heel-measuring device. Link 92 is pivoted to a pair of bell crank levers 96 for parallel movement toward and from the side of the machine. The outer arms of bell crank levers 96 are connected by a 45 link 98. The connections between link 92 and control lever 86 comprise a bell crank lever 100 pivoted upon an arm 102 mounted upon the sliding table 26, one end of this bell crank lever 100 being pivotally connected with the end of the lever 86, while the other end of the bell crank lever 100 is provided with a depending roll 101 adapted to be received within the sides of a groove 50 formed in a part of the link 92. A spring 106 tends to move the lever 86 into a position to close the templet plates and at the same time urges the side gage plate 94 in contact with the side of the heel. A stop member 108 (Fig. 1) adjustably mounted 60 upon a bracket 110 upon the frame of the

machine is so located that it will contact with the lever 86 adjacent to its connection with the ball crank 100 when the sliding table 26 is moved to rearmost position to move the lever 86 against the tension of the 70 spring 106, thus moving the templet plates apart and at the same time moving gage member 94 away from the heel last measured. The roll and groove connection between the sliding table and the heel-measuring device will allow forward and rearward movement of the table 26 without disturbing the connection between the templets and the measuring device.

In the operation of the machine, a shoe 80 mounted upon a last is placed on the spindle of post 20 and moved rearwardly to bring its rand crease into engagement with crease plates 22, the crease plates being moved into the rand crease of the shoe by means of lever 85 24. After the corresponding heel has been placed in the measuring device, hand-wheel 80 is rotated to cause the heel to be engaged by gage members 82, 84. This moves knife bar 62 into position as determined by the 90 length of the heel properly to locate the breast cut and sets the stop 66 for coaction with sleeve 29 of the rotary cutter to limit the movement of the rotary cutter lengthwise of the shoe. The sliding table is then 95 moved forward by means of the hand lever 28, thereby raising the post 20 to press the work firmly into engagement with the crease plates 22 and operating switch 33 to supply current to motor 30. The shaft of the rotary cutter at this time should be positioned in the enlarged portion or vestibule 50 of the horseshoe-shaped slot 44 so that the cutter will not contact with the work as the table 100 is being moved into forward position. As the table is moved forward, the adjustable templet plates 36, 38 are positioned in accordance with the width of the heel in the measuring device, springs 48 and 106 moving plates 36, 38 toward each other until gage member 94 contacts with the side of the heel. When the table has been brought into forward position, the operator grasps the handles of levers 52 and 54 and moves the milling cutter around the horseshoe-shaped slot, 110 thus removing the superfluous material around the periphery of the heel-seat and making a beveled cut so that the heel-seat portion of the sole will correspond in form to the attaching surface of the heel. The 115 trimming operation finished, the operator moves the cutter shaft back into the enlarged portion 50 of the templet slot and actuates lever 28 to slide table 26 back to its rearmost position. This also moves gage member 94 out of engagement with the side of the heel. He then depresses treadle 70 thereby actuating the breast cutting knife 60 to make a transverse cut which will be 120 properly located lengthwise of the shoe for 125 130

coaction with the breast of the heel. As has been noted, this depression of the pedal 70 likewise is effective to raise the post 20 to hold the work firmly in engagement with the crease plates during the breasting operation. This part of the operation finished and the treadle 70 released, the work may be released by actuation of the lever 24 and removed from the machine.

10 If the next shoe to be operated on is to have the same size and style of heel as the last, the heel previously used to control the operation may be left in place on plate 85. Otherwise it is removed and another heel,

15 either the identical heel which is to be attached to the next shoe, or a heel like that one, is placed on plate 85, and the machine is again operated in the manner just described.

20 So much of the patentable subject-matter embodied in the herein-disclosed machine as is disclosed in said Letters Patent of the United States, No. 1,661,391, is not claimed herein since it is claimed in said Letters

25 Patent.

Having described the invention, what I claim as new and desire to secure by Letters Patent of the United States is:

1. A heel-seat fitting machine having, in combination, a work support, a cutter, said work support and cutter being arranged for relative movement to cause the cutter to trim surplus material from the periphery of the heel-seat portion of the sole of a shoe carried by the support, and means for controlling the trimming comprising a measuring device having a member arranged for engagement with the heel or a heel like the heel which is to be attached to the shoe and means for moving said member into engagement with said heel as the cutter and the shoe upon the work support are brought toward operative relation.

2. A heel-seat fitting machine having, in combination, a work support, a cutter, means for causing relative movement of the work support and the cutter to cause the cutter to trim surplus material from the periphery of the heel-seat portion of the sole of a shoe carried by said support, a measuring device having a member arranged for engagement with the heel or a heel like the heel which is to be attached to the shoe, means for moving said member into engagement with said heel as the cutter and the shoe upon the work support are brought toward operative relation, and connections between the measuring device and the means for causing relative movement of the cutter and the work support arranged to control the trimming in conformity with a dimension of said heel as measured by the measuring device.

3. A heel-seat fitting machine having, in combination, shoe-positioning means, a cutter

ter movable to trim surplus material from the periphery of the heel-seat portion of a shoe positioned by said means, and means for controlling the operation of said cutter comprising a measuring device arranged to co-operate with the heel or a heel like the heel which is to be attached to the shoe and having a member arranged to engage the heel as the cutter is moved toward trimming relation to the shoe and movable out of engagement with the heel as the cutter is moved away from trimming relation to the shoe after the conclusion of the trimming operation.

4. A heel-seat fitting machine having shoe-positioning means, a cutter, said shoe-positioning means and cutter being mounted for relative movement to cause the cutter to trim surplus material from the peripheral portion of the heel-seat of a shoe positioned by said means, means for controlling the path of relative movement of said positioning means and cutter, means for adjusting said controlling means to vary the width to which the heel-seat is trimmed, and a heel-measuring device connected with said adjusting means and arranged to measure the width of the heel or a heel like the heel which is to be attached to the shoe and to control the width of the heel-seat formed on the shoe in accordance with the width of said heel.

5. A heel-seat fitting machine having a work support, a cutter, said cutter and work support being mounted for relative movement to cause the cutter to trim surplus material from the periphery of the heel-seat of the sole of a shoe carried by said work support, means for determining the path of relative movement of said cutter and work support, and a heel-measuring device arranged to measure the width of the heel or a heel like the heel which is to be attached to the shoe and connected with and controlling said determining means, thereby causing the heel-seat to be trimmed to a width conforming to that of the heel.

6. A heel-seat fitting machine having shoe-positioning means, a cutter movable to trim surplus material from the periphery of the heel-seat portion of the sole of a shoe positioned thereby, means arranged to measure the length and width of a heel, means controlled by the length-measuring means arranged to control the length to which the heel-seat of the sole is trimmed, and means controlled by the width-measuring means arranged to control the width to which the heel-seat is trimmed.

7. A heel-seat fitting machine having a work support, a cutter, said work support and cutter being mounted for relative movement to cause the cutter to trim surplus material from the peripheral portion of the heel-seat of the sole of a shoe positioned by said

means, means arranged to measure the length and the width of a heel, means controlled by the length-measuring means arranged to control the length to which the heel-seat of the sole is trimmed, and means controlled by the width-measuring means arranged to control the width to which the heel-seat is trimmed.

8. A heel-seat fitting machine provided with a cutter for trimming the periphery of the heel-seat of the sole of a shoe, means for controlling the path of said cutter including means for controlling the extent of operation of the cutter in the direction of the length of the shoe and the operative relation of the cutter and the sole in the direction of the width of the shoe, and means for adjusting said controlling means constructed and arranged to measure both the length and the width of the heel-seat contacting portion of the heel or a heel like the heel which is to be attached to the shoe.

9. A heel-seat fitting machine having a cutter for trimming the periphery of the heel-seat of the sole of a shoe, means for measuring the heel or a heel like the heel which is to be attached to the shoe, mechanism for controlling the extent of operation of said cutter in the direction of the length of the heel-seat of the sole and for controlling the operative relation of the cutter and the sole in the direction of the width of the heel-seat to be formed, and means for adjusting said control mechanism constructed and arranged to adjust the heel-measuring device to measure both the length and width of the heel.

10. A heel-seat fitting machine provided with a rotary cutter arranged to trim surplus material from the periphery of the heel-seat of the sole of a shoe, means for controlling the width to which said cutter trims the heel-seat of the sole, means for controlling the length to which said cutter trims said heel-seat, heel-measuring means constructed and arranged to measure the length and the width of a heel, and means for causing simultaneous and corresponding adjustment of said controlling means and said heel-measuring means.

11. A heel-seat fitting machine provided with a cutter movable to trim surplus material from the periphery of the heel-seat of the sole of a shoe, means for guiding and controlling said cutter, a heel-measuring device arranged to measure the width of the heel to be applied to the shoe, and connections between said heel-measuring device and said guiding and controlling means arranged to adjust the guiding means in conformity with the setting of the heel-measuring device.

12. A heel-seat fitting machine provided with a cutter arranged to trim surplus ma-

terial from the periphery of the heel-seat of the sole of a shoe, means for controlling the width to which said cutter trims the heel-seat of the sole, means for controlling the length to which said cutter trims the heel-seat, and heel-measuring mechanisms arranged to measure the length and the width of a heel, said length-measuring mechanism being connected to the mechanism for controlling the length to which the cutter trims the heel-seat and said width-measuring mechanism being connected to the means for controlling the width to which the cutter trims the heel-seat of the sole.

13. A heel-seat fitting machine provided with a cutter adapted to be moved around the periphery of the heel-seat of the sole of a shoe to trim surplus material from the same, an adjustable templet for controlling the path of movement of said cutter, means for adjusting said templet, resilient means urging said adjusting means in one direction, heel-measuring mechanism for measuring a dimension of a heel, and connections between the heel-measuring mechanism and the adjusting means arranged to cause the adjusting means to adjust the templet in accordance with a dimension of a measured heel.

14. A heel-seat fitting machine having a cutter arranged to be moved around the periphery of the heel-seat of the sole of a shoe to trim surplus material therefrom, means for controlling each of two dimensions of the path of movement of said cutter, means for adjusting each of said controlling means, a heel-measuring device arranged to measure two dimensions of a heel, manually operated means connected to one of said adjusting mechanisms to cause it to be positioned in accordance with a measured dimension of a heel, and connections between the other heel-measuring mechanism and the other adjusting mechanism arranged to set the controlling means in accordance with the other dimension of the heel.

15. A heel-seat fitting machine provided with a rotary cutter arranged to be moved around the periphery of the heel-seat portion of the sole of a shoe to trim surplus material therefrom, a templet adjustable to control the path of movement of said rotary cutter, means for limiting the length of the path of movement of the cutter within said templet, heel-measuring mechanism arranged to measure both the length and the width of a heel, means connecting the length-measuring mechanism with the means for limiting the length of the path of movement of the cutter, manually operated means for adjusting said length-limiting mechanism and said length measuring mechanism, and means controlled by the width-measuring mechanism for adjusting the templet to control

the width to which the heel-seat is trimmed in accordance with the setting of the heel width-measuring mechanism.

16. In a heel-seat fitting machine, shoe-supporting and positioning mechanism, a slideable table movable to the rear to facilitate the positioning of a shoe in the supporting mechanism, a trimming cutter carried by said slideable table and adapted to be moved around the periphery of the heel-seat of the sole of the shoe to trim the same, means on said table for controlling the path of the cutter, means for adjusting said controlling means, a heel-measuring device mounted upon a fixed part of said machine, and means operatively connecting said heel-measuring device with said adjusting means.

17. In a heel-seat fitting machine, a frame, shoe-supporting and positioning means on said frame, a slideable table movable toward and away from said shoe-supporting means, a rotary trimming cutter carried on said slideable table, an adjustable templet controlling the path of movement of said rotary cutter, means tending to move the templet into position for the narrowest path of movement of the cutter, and a fixed stop on the frame of said machine coacting with said templet-adjusting means in one position of the slideable table to move the templet into its other extreme position.

18. In a heel-seat fitting machine, a frame, shoe-supporting and positioning means on said frame, a slideable table movable toward and away from said shoe-positioning means, a rotary trimming cutter carried on said table, a two-part templet for controlling the path of movement of said cutter, resilient means urging said templet into closed position, a lever for opening the templet, means supported upon a fixed part of the frame of the machine for measuring the width of a heel, means connecting the templet-opening mechanism with said width-measuring mechanism in any position of the slideable table, and a fixed stop coacting with said templet-opening mechanism and said width-measuring mechanism when the table is in its inoperative position and arranged to open the templets and to open the measuring mechanism.

19. In a heel-seat fitting machine, a frame, shoe-supporting and positioning means on said frame, a cutter, said shoe support and cutter being arranged for relative movement to cause the cutter to trim surplus material from the periphery of the heel-seat portion of the sole of a shoe carried by the supporting means, means for controlling the trimming operation comprising a measuring device having a member arranged for engagement with the heel or a heel like the heel which is to be attached to the shoe, and means for moving said measuring device out

of engagement with the heel to allow the removal and replacement of a heel as the relative movement of the work support and cutter brings these parts to inoperative position.

20. In a heel-seat fitting machine, a frame, shoe-supporting and positioning means on the frame, a trimming cutter movable to remove surplus material from the periphery of the heel-seat portion of the sole of a shoe carried by the work-supporting means, means for controlling the operation of said cutter comprising a measuring device arranged for movement into and out of engagement with the heel or a heel like the heel which is to be attached to the shoe, and means for moving said measuring device out of engagement with the heel as the cutter is moved out of operative relation to the shoe.

21. In a heel-seat fitting machine, the combination of a frame, shoe-supporting and positioning means on said frame, a slideable table movable toward and away from said shoe-positioning means, a rotary trimming cutter carried on said table, means for controlling the path of movement of the trimming cutter comprising a measuring device movable into engagement with the heel or a heel like the heel which is to be attached to the shoe and movable out of engagement therewith to allow the removal and replacement of the heel, and means for moving said measuring device out of engagement with the heel when the slideable table is moved away from the shoe-positioning means into inoperative position at the conclusion of the trimming operation.

22. A heel-seat fitting machine having, in combination, means for measuring the width of a heel to be attached to a shoe, and a cutter under the control of said measuring means arranged to trim surplus stock from the heel-seat of the sole of a shoe to fit the heel-seat for the reception of the measured heel or a heel like that heel.

23. A heel-seat fitting machine having, in combination, means for measuring the width of a heel, a cutter for trimming surplus material from the peripheral portion of the heel-seat of the sole of a shoe, and connections between the measuring means and the cutter constructed and arranged to cause the measuring means to control the dimensions to which the heel-seat is trimmed by the cutter.

24. A machine for use in the manufacture of shoes having, in combination, a cutter arranged to trim surplus material from a shoe part, a guide for said cutter adjustable to control the trimming of shoe parts of different widths, means for measuring the width of a shoe part, and connections from said measuring means to said guide to adjust the

guide in accordance with the width of the measured part.

25. A machine for use in the manufacture of shoes having, in combination, a cutter for trimming surplus material from the periphery of a shoe part to fit said shoe part for the reception of another part, a horseshoe-shaped guide for said cutter, measuring means arranged to measure the width of a

shoe part, and connections from said measuring means to said horseshoe-shaped guide arranged to vary the spread of the horseshoe-shaped guide in accordance with the width of the measured part.

In testimony whereof I have signed my name to this specification.

WILLIAM C. STEWART.
